Inventor
John D. Hilliard

UNITED STATES PATENT OFFICE.

JOHN D. HILLIARD, OF SCHENECTADY, NEW YORK, ASSIGNOR TO GENERAL ELECTRIC COMPANY, A CORPORATION OF NEW YORK.

ELECTRIC SWITCH.

Application filed October 23, 1926. Serial No. 143,755.

My invention relates to electric switches of the type having main current carrying contacts and separate auxiliary or arcing contacts which, when the switch opens, separate 5 subsequently to the main contacts and between which the final break in the circuit is made. An object of my invention is to provide an improved construction of switch of this type whereby better insulation of the live 10 parts of the switch may be effected and all possibility of an open arc at the main contacts is avoided.

My invention will be better understood from the following description taken in connection 15 with the accompanying drawing, and its scope will be pointed out in the appended claims.

Referring to the drawing, Fig. 1 shows a side elevation partly in section of a switch 20 embodying my invention, and Fig. 2 is a cross-sectional view taken on line 2-2 of Fig. 1.

I have shown the switch supported on a plate 1 by means of two insulator bushings 2 through which extend the connecting studs 3 having nuts 4 and comprising the switch terminals. Each bushing supports a pressure vessel 6 which preferably is a steel shell whose top is closed by the cover 7 held down by the 25 rods 8 threaded into the contact clamp 9. The latter has a central opening into which is secured the contracted bottom portion 10 of the vessel and is itself secured to the contact head 11 on the upper end of the stud by a suitable strap 11' an eye bolt and nut. Firmly secured in the bottom of the vessel 6 is the fixed auxiliary contact 12 in which engages the movable auxiliary contact rod 14. The two contact rods 14 extend out through the tops 30 of the vessels through insulators 15 and are joined together by the yoke 16. Operating rod 18 passes through the yoke and at that point carries a spool 19 having sliding engagement with the yoke and providing a certain amount of lost motion between the rod and the yoke. The compression spring 20 between the yoke and the upper flange of the spool resiliently presses the yoke toward the lower flange of the spool. The vessels 6 are 35 shown provided with separating and cooling chambers 21 to the tops of which connect discharge pipes 22.

Arranged between the two vessels 6 is a third vessel 25 preferably of insulating material, as shown, in which vessel the main cur-

rent-carrying contacts separate in an insulating liquid. The vessel 25 may be of molded insulating material in opposite sides near the bottom of which the main fixed contacts 26 may be molded. The vessel is arranged so 40 that these contacts are directly opposite the contact clamps 9 and are secured directly therewith by bolts 27. As so constructed the vessel 25 is supported by its main contacts 26 and the contact clamps 9. The vessel contains 45 a suitable insulating liquid 28 and has a cover 29 through an opening in which slides the operating rod 18. The main movable contact or bridging member 30 is secured by the bolt 31 to the cross head 32 which slides vertically 50 on the two guide pins 33. These pins are shown secured in the bottom of the vessel and are surrounded by compression springs 34 beneath the cross head to force the bridging member 30 out of contact with the main fixed 55 contacts 26 when the operating rod is raised. A detachable connection is provided between the operating rod and the bridging member by having the bolt 31 fit loosely into a bore in the end of the operating rod. In moving the 60 switch from the position illustrated to open circuit position the operating rod in moving upward is followed by the cross head 32 and the bridging member 30 under the influence of the springs 34 until their movement is arrested by the heads on the guide pins, thus 65 separating the main current carrying contacts. During this movement or a part thereof, the yoke 16 remains fixed, the coil spring 20 assisting in holding it in fixed position. 70 At length the lower flange of the spool engages the yoke, the rod and operating mechanism therefor having gained speed in the meantime, and now the yoke with the connected auxiliary contact rods 14 rise as a 75 unit to effect the final quick break of the circuit.

This construction permits the main contacts to separate before the auxiliary contact rods are moved. There is also no danger 80 from any arcing at the main contacts and insulation of the live parts of the switch are simplified and facilitated.

What I claim as new and desire to secure by Letters Patent of the United States, is,—

1. An electric switch comprising spaced pressure vessels adapted to contain insulating liquid and each having a fixed auxiliary contact at the bottom and a cooperating movable auxiliary contact rod extending through 110

- the top thereof, a yoke member connecting the movable contact rods, a separate vessel adapted to contain insulating liquid arranged between said vessels having main 5 fixed contacts therein arranged opposite and connected to the respective auxiliary fixed contacts, a main movable contact arranged to bridge said main fixed contacts, means limiting the open circuit movement of said main 10 movable contact and an operating rod arranged to make engagement at one end with said main movable contact and to have an operative connection at an intermediate point with said yoke member.
- 15 2. An electric switch comprising a pair of spaced insulator bushings, a stud in each bushing, a pressure vessel carried by each bushing adapted to contain insulating liquid, a movable contact rod extending through 20 the top and a fixed auxiliary contact in the bottom of each vessel, means comprising contact clamps for connecting the studs with the vessels, an insulating vessel arranged between said vessels having main contacts 25 therein, conductors connecting said main contacts with said clamps and supporting the insulating vessel from the clamps, a main contact bridge adapted to engage said main contacts, and a single operating rod connected at spaced points to said contact rods and said main contact bridge.
- 30 3. An electric switch comprising a pair of spaced pressure vessels each adapted to contain insulating liquid and cooperating fixed and movable auxiliary contacts immersed therein, a separate vessel of insulating material arranged between said vessels and adapted to contain insulating liquid, fixed main contacts therein connecting respectively with said fixed auxiliary contacts, 35 a movable main contact bridge therein, guiding means for said bridge, resilient means for moving the bridge to open circuit position, a yoke connecting the movable auxiliary contacts, an operating rod connected 40 to said yoke and said bridge, a lost motion connection between the yoke and the rod and resilient means for taking up the lost motion in one direction.
4. An electric switch comprising a vessel 45 adapted to contain insulating liquid, spaced fixed contacts therein, a cooperating movable bridging contact, a cross head secured thereto and arranged transversely thereof, guide pins for said cross head spaced from 50 the fixed contacts, means for resiliently forcing the bridging contact away from the fixed contacts, and an operating rod detachably connected to the cross head.

In witness whereof, I have hereunto set my hand this 2nd day of October, 1926.

JOHN D. HILLIARD.
